UNITED STATES PATENT OFFICE.

HENRY T. PAISTE, OF PHILADELPHIA, PENNSYLVANIA, ASSIGNOR TO H. T. PAISTE COMPANY, OF PHILADELPHIA, PENNSYLVANIA, A CORPORATION OF PENNSYLVANIA.

CUT-OUT.

1,226,584.

Specification of Letters Patent.

Patented May 15, 1917.

Application filed September 9, 1915. Serial No. 49,764.

To all whom it may concern:

Be it known that I, HENRY T. PAISTE, a citizen of the United States, residing in Philadelphia, Pennsylvania, have invented 5 certain Improvements in Cut-Outs, of which the following is a specification.

One object of this invention is to simplify and cheapen the construction of fuse or lamp receptacles or sockets such for example 10 as are commonly used in cut-outs, the design and arrangement of parts being such that less material is required than has heretofore been considered necessary and at the same 15 time better electrical contact between certain of the parts is insured.

These objects and other advantageous ends I secure as hereinafter set forth, reference being had to the accompanying drawings, in which,

20 Figure 1 is a perspective view of a cut-out in which the fuse receptacle is made according to my invention;

Fig. 2 is a vertical section taken through one of the fuse receptacles and the terminals 25 associated therewith;

Figs. 3 to 6 inclusive are perspective views of certain of the detail parts of the cut-out;

Fig. 7 is a plan of the threaded receptacle shell and several of its associated parts; 30 and

Figs. 8 and 9 are respectively a plan and a perspective view of the shell itself.

In the above drawings 1 represents the porcelain body or casting of a cut-out having 35 two substantially cylindrical chambers 2 and 3 for the reception of two fuse receptacles, and provided with two transversely extending channels 4 and 5 for the reception of a pair of line wires. Each of the receptacles includes a substantially cylindrical threaded metal shell concentrically mounted within one of the cylindrical chambers of the base 1 and made in the form of a cup from whose bottom is cut a transverse tongue 45 7 which is bent through an angle of 180° so that it projects in a plane slightly above that of the bottom to one side of said shell. Said tongue is designed to extend through the vertical opening in the side of its chamber in the porcelain base and lies within a recess formed adjacent thereto. Within the metal shell 6 is mounted a metal plate 8 including a portion having a slot 9 of the same width as the slot from which the 55 tongue 7 was cut and made of generally cir-

cular outline so that it will fit within the bottom of said shell 6. From said body portion a projection 10 extends for a distance substantially equal to the length of the tongue 7 and it is noted that this member 8 is made of metal considerably thicker than that of the shell 6, having two oppositely placed lugs 11 at the end of the extension 10 and formed with a threaded hole 12 concentric with said end.

60 It is noted that while the two arms or branches 13 of this member 8 rest upon the side portions of the bottom 14 of the shell 6, the extension 10 projects under and in engagement with the tongue 7; which adjacent 65 its outer end has a hole 15, through which passes a screw 16 threaded into the opening 12 of the member 8 so as to form a means for the attachment of a branch conductor.

The metal shell 6 is held in place by a 70 fiber washer 17 placed in its bottom in engagement with the branches 13 and engaged by a washer 18 through which a screw 19 passes centrally, into an opening in the center of the bottom of the chamber in which said shell is mounted. Said screw is threaded 75 into an opening in the end of a connecting strip 20 which extends in a cavity formed in the under side of the porcelain base 1, into one of the channels 4 or 5 (in the case illustrated the channel 5) where it terminates in a flat portion 21. This latter has a coöperating conductor-clamping plate 22 held to it by a screw 23 and both it and said plate are transversely grooved or bent out to form 80 a channel for the reception of the properly bared conductor which is to be connected to the strip 20.

85 Similarly the second shell 6a of the cut-out is held in place by the same means as those heretofore described in connection with the shell 6, excepting that its conducting strip 20a, shown in dotted lines in Fig. 2, is of such a length that its outer end extends into the channel 4 where it is provided 90 with a clamping plate 22a and a clamping screw 23a. The head of the screw 19, which is concentric with its metal shell 6 or 6a as the case may be, constitutes one of the terminals of the fuse receptacle, whose other terminal is provided by the threaded shell, from which said screw is insulated by the fiber disk or washer 17, it being noted that the screw passes through the substantially elliptical opening defined by the branches 13 119

of the member 8 and by the sides of the slot in the bottom 14 of the shell 6, but without contacting with the metal thereof.

With the above described arrangement it will be noted that the piece cut out from the bottom of the shell 6 is utilized to insure good electrical connection with a branch conductor engaged by the screw 16, since said conductor is necessarily confined between said screw (whose head itself constitutes a washer), and the tongue 7, so that said conductor is made to electrically engage the metal of the shell itself. At the same time the shell is more firmly than heretofore held in place, since the screw 16 passing through the hole 15 into the hole 12, insures that the various parts are retained in their proper positions.

I claim;—

- 20 1. The combination of a metal shell having a tongue cut from its bottom and bent through an angle of substantially 180° ; a metal piece extending into the lower part of said shell and projecting under said tongue; 25 a contact in the shell but insulated from the same; and means for connecting a conductor to said contact.
2. The combination of a metal shell hav-

ing a tongue cut from its bottom and bent through an angle of substantially 180° ; a metal piece in engagement with a portion of the bottom of the shell and extending in contact with said tongue; means for connecting a conductor to the tongue and to said piece; and a central contact for said shell.

3. The combination of a threaded metal shell having a metal tongue cut from its bottom to form a slot and bent through an angle of substantially 180° so as to project to one side of said shell; a forked metal plate having its branches in engagement with the bottom of the shell on either side of the slot and having its body projecting in contact with the tongue; a binding screw passing through the tongue and threaded into said plate; with a central contact for said shell.

4. The combination of a metal shell having a tongue cut from its bottom and bent at an angle to the plane thereof; a metal piece in engagement with a portion of the bottom of the shell and in contact with said tongue; means for connecting a conductor to said tongue and to said piece; and a central contact for the shell.

HENRY T. PAISTE.
